Primary Examiner — Susan E Krakower*Assistant Examiner* — L. A. Grabenstetter(74) *Attorney, Agent, or Firm* — Sughrue Mion, PLLC(57) **CLAIM**

The ornamental design for a digital camera, as shown and described.

DESCRIPTION

FIG. 1 is a front perspective view of a digital camera, showing the new design;

FIG. 2 is a perspective view of the embodiment, viewed from the rear side thereof;

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines depict unclaimed portions of the digital camera.
